(57) **CLAIM**

The ornamental design for a hanger bracket for cabinet door storage rack, as shown and described.

DESCRIPTION

FIG. 1 is a perspective view of a hanger bracket for cabinet door storage rack showing our new design;

FIG. 2 is a top plan view thereof;

FIG. 3 is a front elevational view thereof;

FIG. 4 is a rear elevational view thereof;

FIG. 5 is a bottom plan view thereof; and,

FIG. 6 is a side elevational view thereof taken from the right side, the opposite side appearing as a mirror image.
